LATCH

Herbert Quigley and Herman Ter Meer, Grand Rapids, Mich., assignors to National Brass Company, Grand Rapids, Mich., a corporation of Michigan

Application May 29, 1944, Serial No. 537,820

4 Claims. (Cl. 292—169)

This invention relates to a latch to be secured at and within the edge portions of a door, a cylindrical hole being bored inwardly from the edge of the door to receive the latch housing and the bolt mounted therewithin, and a transverse opening bored through the door across said cylindrical opening for the passage of the operating bar, to the ends of which, normally, suitable knobs or equivalents for hand engagement are connected.

Heretofore patents, Nos. 1,871,633 and 1,883,099, for similar latch constructions have been granted. In the present invention, a simplified and more economical latch construction is produced and one in which the parts may be more easily and economically produced and assembled and a shortening of the over all length of the latch with consequent economy in manufacture and installation.

A preferred construction embodying the invention, and various other objects and purposes than those enumerated coming therefrom may be understood from the following description, taken in connection with the accompanying drawing, in which,

Fig. 1 is a horizontal longitudinal section through the latch of our invention.

Fig. 2 is a longitudinal horizontal section through the outer latch housing, the interior bolt mechanism being shown in plan.

Fig. 3 is a longitudinal vertical section substantially on the plane of line 3—3 of Fig. 2.

Figs. 4 and 5 are transverse sections on the planes of lines 4—4 and 5—5, respectively, of Fig. 2, and

Fig. 6 is a perspective view of the inner latch bolt mechanism insertable at the open end of the cylindrical housing therefor.

Like reference characters refer to like parts in the different figures of the drawing.

In the construction, an outer housing or casing 1 of sheet metal of cylindrical form has an inner closed end 2 and an open outer end with an outwardly extending annular flange 3. Near the inner end of the housing or casing, transverse circular openings 4 are made through opposite sides thereof, and substantially midway between the ends of the housing at opposed sides, the metal is slit and pressed inwardly for short distances, as at 5, to provide abutments or stops, 50 the purpose of which will later appear.

Within this housing or casing the movable latch bolt is located. It includes a head 6 with an inclined outer end or face 7 which, coming against a suitable strike on a door jamb, will serve as

a cam to force the head 6 and parts connected therewith inwardly through the well known cam action under which latch bolts of this character operate. A cylindrical sleeve 8 extends inwardly 5 a short distance from the inner side of the head 6 and adjacent its inner end is provided with diametrically opposed outwardly extending lugs 9 as shown.

Associated with the cylindrical portion 8 is a 10 barrel of sheet metal formed in two semi-cylindrical sections 10, each at its front end having an outwardly extending annular flange 11 and at adjacent edges between its ends being cut away to provide longitudinal slots 12 in the 15 assembled barrel to which the lugs 9 extend. Each of the semi-cylindrical halves 10 of the barrel near its rear end has a semi-circular plate 13 secured therein by brazing, welding, soldering or other preferred permanent connection. A 20 coiled spring 14 of light strength is located at one end against the two contacting semi-circular members 13 and at its other end against the inner end of the head 6, said spring extending through the hollow cylindrical part 8 as best 25 shown in Fig. 3. A heavier coiled spring 15 is located around the barrel, bearing at one end against the flanges at 11 and at the other end against the previously described stops or abutments 5 (see Fig. 2).

30 At the rear or inner end of the barrel 10, a stirrup member of sheet metal having two spaced sides 16 is provided which, at their outer ends, are formed with spaced inwardly turned ears 17 which pass through suitable slots cut in the 35 barrel sections 10, thereby holding them together at their inner ends in addition to the holding of said parts together by the surrounding spring 15. The inner ends of the sides 16 of the stirrup are connected by an integral cross piece which 40 is pressed and formed into a triangular shaped cam as indicated at 18. Such interior bolt structure when assembled is readily inserted at the outer open end of the housing or casing 1 until the inner end of the spring 15 engages against the 45 stops 5; and afterward by pushing inwardly against the outer end of the head 7 and compressing the spring 14 until the head reaches the flanges 11, and thereafter compressing the spring 15, the stirrup member of the bolt may be moved to the position indicated in dotted lines in Fig. 3.

In such dotted line position the operating means for the bolt may be passed through the 55 openings 4. It consists of a bar 19, the intermediate portion of which is shaped, as at 20,

into a section semi-cylindrical in cross section and at its inner side conforming to the sides of the triangular shaped cam 18, which cam seats therein upon release of the latch bolt and its outward movement under the influence of the springs 14 and 15 as shown in Figs. 1, 2 and 3. It will be apparent that the spring 14 moves the head 6 outwardly until the lugs 18 reach the outer ends of the slots at 12, and the spring 15 will move the described barrel and stirrup connected therewith outwardly until the triangular shaped cam portion at 18 is received in the recess of the part 28 of the operating bar 19. Said bar 19 may have at each end, at the outer sides of a door, a knob or other conventional hand engaging member secured thereto in the usual manner.

With this construction the length of the outer casing or housing 1 is decreased over that shown in said previous patents, which have housings lengthened in order to provide space for the heavier spring which projects the bolt therein outwardly to normal position. The parts 18 of the barrel are substantial duplicates, both easily formed and pressed from sheet metal as is also the connecting stirrup and the cylindrical portion 8 connected to the head 6 of the latch bolt. The retraction of the latch bolt for opening a door is by turning the operating bar 19 about its longitudinal axis whereupon, through the cam action of the section 28 engaging against the triangular cam 18, the bolt is retracted with a compression of the spring 15. Referring to Fig. 3 it will be noted that when the latch bolt is retracted to its extreme position the triangular cam projection 18 has its pointed portion still projecting slightly across the openings at 4 so that there is always a stop against a complete rotation of the operating bar. This is by reason of the positioning of closed end 2 of the housing in such proximity to the openings at 4 that the stirrup member is stopped against movement when it engages against such end 2 as shown in dotted lines in Fig. 3. In closing the door only the head 6 and attached part 8 are moved inwardly with a compression of the spring 14 which will yield and compress before any force strong enough to compress the spring 15 is generated.

The construction is practical and economical and its installation on a door is simply a boring the cylindrical holes required, one to receive the latch bolt housing 1 and the other for the passage of the transverse operating bar 19.

The invention is defined in the appended claims and is to be considered comprehensive of all forms of structure coming within their scope.

We claim:

1. In a latch construction, a cylindrical housing having an open end and having inwardly pressed stops at its sides intermediate said ends, a latch bolt including a cylindrical barrel located within said housing, said barrel at its outer end having an outwardly extending flange, a coiled spring around said barrel between said flange and said stops, a keeper engaging head operatively associated with said barrel and having a telescoping portion extending into the barrel and a light spring between said head and the barrel normally moving the head in an outward direction.

2. A latch construction comprising a cylindri-

cal barrel open at one end and intermediate its ends having inwardly extending stops, a hollow barrel comprising two semi-cylindrical sections located within the housing, said sections at their outer ends having outwardly extending flanges, a coiled compression spring around the barrel between said flanges and said stops, a stirrup member having spaced arms and a connecting cross piece at the inner ends thereof, the opposite ends of said arms having spaced inwardly turned fingers, and said semi-cylindrical sections of the barrel having openings through which said fingers pass, and a head normally projecting beyond the open end of the housing provided with a cylindrical portion at its inner end telescopingly received within said barrel, and spring means between the barrel and said head for normally forcing the head in an outward direction combined with interengaging means on the barrel and said telescoping portion for limiting outward movement thereof.

3. A construction having the elements in combination defined in claim 2, said cross connecting portion of the stirrup being formed into a triangular shaped forwardly extending cam, said housing having opposed openings through the sides thereof near its inner closed end, and an operating rod passing through said openings and between the sides of said stirrup member having an offset section provided with a side conforming to said triangular shaped cam for retracting said barrel against said compression spring on turning the rod about its longitudinal axis.

4. A latch construction comprising, a cylindrical housing open at one end and having a bottom at the other end and, intermediate its ends having portions pressed inwardly to provide stops, said housing a distance from the bottom end having transverse circular openings therethrough, a barrel located within the housing, a coiled compression spring around the barrel bearing at one end against said stops, said barrel at its outer end having outwardly extending means against which the other end of the spring bears, a spring actuated bolt having an inner end telescopingly received within said barrel, a stirrup member having spaced arms connected with the barrel adjacent the inner end of the barrel said stirrup member having a forwardly extending triangular shaped cam cross member at its inner end, and an operating rod passing through said transverse openings in the housing and extending between the sides of said stirrup member having an offset section provided with a side conforming to said triangular shaped cam for retracting said barrel against the compression spring on turning the rod about its longitudinal axis, the bottom of the housing being disposed in sufficiently close proximity to the openings of the barrel that when the stirrup member is moved inwardly until it engages the bottom of said housing the forward portions of said triangular shaped cam extends a short distance forward of the rearmost portions of the openings through the housing to provide a stop against the operating bar turning beyond a predetermined position, being stopped on its turning movement by engagement against said forward projecting portion of the cam cross member
